(57) **CLAIM**

The ornamental design for a currency cassette, as shown and described.

DESCRIPTION

FIG. 1 is a perspective view of a first embodiment of a currency cassette according to our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a currency cassette according to a second embodiment of our design which shows all of the alternative features; and,

FIG. 9 is a perspective view of a currency cassette according to a third embodiment of our design which shows all of the alternative features.

The dotted-line features shown in various figures are exemplary only and form no part of the claimed design.
